AUTOMATICALLY THREADING SHUTTLE

Isaac Snow, Lawrence, Mass., assignor to Draper Corporation, Hopedale, Mass., a corporation of Maine

Application July 30, 1934, Serial No. 737,553

4 Claims. (Cl. 139—223)

The present invention pertains to loom shuttles and has more particular reference to the threading feature of automatically threading shuttles such as are used with bobbin changing looms.

Shuttles of the type mentioned are usually provided with a threading block, so-called, in which the filling partially threads during the first pick of the shuttle after the transfer thereof to of a new filling supply. During the second pick after transfer the filling is intended to slide down an appropriate passage into the side delivery eye. Instead, it frequently becomes completely unthreaded from the eye, by reason of its passing rearwardly out of control of the horn which is provided for preventing such unthreading.

Accordingly, it is the principal object of my invention to provide a novel and efficient means for preventing the filling from escaping from the horn once the filling has assumed its partially thread position.

Other objects will be hereinafter more specifically enumerated, or will become obvious as the description proceeds.

I have accomplished the aforementioned object of my invention by providing the rearward free end of the horn with a downwardly and forwardly extending thread guard, and by providing a supporting bridge just outwardly of the thread guard for supporting the partially threaded filling above the bottom of the thread guard. The bridge may be in the form of a forwardly extending finger which is spaced above the bottom of a groove, thereby providing two alternate paths for the partially threaded filling. Both of said paths are closed rearwardly, and accordingly prevent the filling from becoming unthreaded.

The preferred embodiment of my invention is illustrated on the accompanying drawing, of which:

Fig. 1 is a plan view of the end of a shuttle containing a threading block of the present invention;

Fig. 2 is a perspective view of the same;

Fig. 3 is a front elevation of the threading block detached from the shuttle; and

Fig. 4 is a sectional view taken approximately on line 4—4 of Fig. 1.

The shuttle illustrated on the drawing includes a shuttle body 1, and suitable means (not shown) for releasably holding a bobbin 2 in a cavity 3 in the shuttle body. The shuttle body 55 is recessed as at 4 to receive the threading block

5 of the present invention. The shuttle body may also be recessed to provide a groove 6 which extends outwardly from the threading block toward the tip of the shuttle for a purpose to be hereinafter described. A suitable passage 7 leads from the groove to the usual side-delivery eye 8.

It is here noted that I employ such terms as "forwardly", "outwardly", and "above" as though the shuttle were positioned in a loom. Thus, the 10 wall 9 of the shuttle body is the front wall, the top of the wall is indicated at 10, and the tip 11 points in a direction "outwardly" of the shuttle.

The threading block includes front and rear walls 12 and 13, respectively, which define a 15 thread passage 14 extending longitudinally of the shuttle. The thread passage is preferably open at the top for the free entrance of the filling thread. A horn 15 projects from the front wall 12 rearwardly over the thread passage, and 20 the outer and forward edge of the horn constitutes one side of the passage 7.

When a new bobbin is first transferred to the shuttle the filling end extends from the bobbin upwardly and outwardly to a thread holder (not shown) on the loom. Then, when the shuttle is picked, the filling swirls or balloons in unwinding from the bobbin and becomes partially threaded into the threading block. I use the term "partially threaded" in its technical sense, 30 to mean that the filling extends from the bobbin, through the thread passage 14, beneath the horn 15, and on outwardly to a fixed holding means, as shown at 16 on Fig. 1.

The partially threaded filling is supposed to 35 slide down the passage 7 into the side delivery eye during the second pick after transfer. However, with prior shuttles difficulty has been experienced with the filling becoming unthreaded from its partially threaded position instead of 40 entering the passage 7 as it should. The shuttle of the present invention provides means whereby the filling is positively prevented from unthreading from its partially threaded position.

A hook-like thread guard 16 projects from the 45 rearward free end of the horn for preventing the partially threaded filling from moving rearwardly. This thread guard extends downwardly, or outwardly and downwardly, into the groove 6, and then forwardly, the groove providing a 50 space about the horn and thread guard for the entrance of the filling. In order to support the filling and prevent its dropping or twisting out of control of the thread guard a bridge 17 is provided, just outwardly of the thread guard. 55

The bridge 17 extends forwardly from the rear wall of the threading block and below the under surface of the horn 15, thus providing a path below the horn for the partially threaded filling 1. The bridge is above the bottom of the thread guard 16, wherefore the latter closes the rearward side of the said filling path.

The embodiment illustrated actually provides two separate paths for the partially threaded filling. This is accomplished by forming the bridge as a finger which is spaced above the bottom of the groove 6. The finger extends forwardly to a point approximately in alignment with the front wall of the threading block, there 10 by providing alternate, vertically spaced paths for the partially threaded filling. It is desirable that the filling pass about the end of the finger into the lower path, but the construction is such that this is not imperative. It is noted 15 particularly that the partially threaded filling 20 may fail to enter the lower path if it is very light or does not balloon much.

It will be noted that both of the paths for the partially threaded filling are closed rearwardly 25 and both are opened forwardly to communicate with the passage 7. I find that with the present construction it is not necessary that the longitudinal thread passage 14 be provided with hooks, covers or guards, and this passage is accordingly 30 shown as being open and unobstructed.

Having fully disclosed the preferred embodiment of my invention, I claim:

1. An automatically threading loom shuttle comprised of a shuttle body, a threading block 35 in said shuttle body having a longitudinally extending thread passage, said threading block being provided with a horn which extends rearwardly over said thread passage, a thread guard comprised of a member curving downwardly, outwardly and forwardly from the rearward free end of said horn, said member extending into a groove provided therefor in said shuttle body, and a thread supporting bridge adjacent to but outwardly of said horn and member, said bridge extending transversely of said groove above the bottom thereof and lower than the under surface 40 of said horn to provide a support for the partially threaded filling which prevents the latter from unthreading about said member.

50 2. An automatically threading loom shuttle comprised of a shuttle body, a threading block in said shuttle body having front and rear walls

defining a thread passage, said threading block being provided with a horn which projects from said front wall rearwardly over said thread passage, a thread guard comprised of a member curving downwardly, outwardly and forwardly from the rearward free end of said horn, said member extending into a groove provided therefor in said shuttle body, and a thread supporting bridge adjacent to but outwardly of said horn and member, said bridge extending from said rear wall forwardly above the bottom of said groove to a point forwardly of said member, the top of said bridge being lower than the under surface of said horn to provide a path therebetween for the partially threaded filling.

15 3. An automatically threading loom shuttle comprised of a shuttle body, a threading block in said shuttle body having front and rear walls defining a longitudinally extending thread passage, said threading block being provided with a 20 horn which extends rearwardly over said thread passage, a thread guard on the rearward free end of said horn projecting downwardly into a groove provided therefor in the shuttle body, and a finger adjacent to but outwardly of said horn and guard 25 which finger projects forwardly from said rear wall to a point forwardly of said guard, the said finger being below the level of the under surface of said horn and above the bottom of said groove to thereby provide alternate paths through which 30 the partially threaded filling may run during the first pick after the transfer.

4. An automatically threading loom shuttle comprised of a shuttle body, a threading block in said shuttle body having front and rear walls 35 defining a thread passage, said threading block being provided with a horn which projects from said front wall rearwardly over said thread passage, there being a groove in said shuttle body extending outwardly from said thread passage and 40 providing a space beneath said horn for the partially threaded filling, a finger projecting forwardly from said rear wall below the level of the under surface of said horn and above the bottom of said groove to thereby divide said space 45 into two alternate paths for the partially threaded filling, and a thread guard member projecting from the rearward free end of said horn downwardly and forwardly to prevent the partially threaded filling from unthreading from the upper 50 of said paths.

ISAAC SNOW.
